FLEXIBLE HOSE

John Greczin, Philadelphia, Pa., assignor to Fidelity Machine Company, Inc., Philadelphia, Pa., a corporation of Pennsylvania

Application January 23, 1957, Serial No. 44,580

Term of patent 14 years

(Cl. D43—1)

Fig. 1 is a side elevational view of a flexible hose showing my new design with a portion omitted to indicate indeterminate length.

Fig. 2 is an elevational view of an enlarged fragmentary section of the hose shown in Fig. 1.

The dominant features of my design reside in the portions shown in full lines.

I claim:

The ornamental design for a flexible hose, substantially as shown and described.
